UNITED STATES PATENT OFFICE.

CECELIA H. GOLDMAN, OF ST. LOUIS, MISSOURI.

SHOW-TOP.

SPECIFICATION forming part of Letters Patent No. 703,912, dated July 1, 1902.

Application filed November 7, 1901. Serial No. 81,435. (No model.)

To all whom it may concern:

Be it known that I, CECELIA H. GOLDMAN, a citizen of the United States, residing at St. Louis, State of Missouri, have invented certain new and useful Improvements in Show-Tops, of which the following is a full, clear, and exact description, reference being had to the accompanying drawings, forming a part hereof.

10 My invention has relation to improvements in show-tops; and it consists in the novel construction and arrangement of parts more fully set forth in the specification and pointed out in the claims.

15 In the drawings, Figure 1 is a front elevation of my invention with one of the end bars partly broken or in section to show the groove formed therein, the device being shown closed. Fig. 2 is an enlarged detail showing the locking device for the sliding panel. Fig. 3 is a perspective of the upper corner of the sliding panel. Fig. 4 is an elevation thereof with parts broken away. Fig. 5 is a vertical section on line 5 5 of Fig. 1, and Fig. 6 is a front 25 elevation showing a sliding panel in an open position.

The present invention is an improvement on the construction of show-tops shown and described in United States Letters Patent, 30 dated July 2, 1895, and numbered 541,927, granted to Henrietta Goldman, and has for its object to materially simplify the details of construction shown in said patent.

In detail the invention may be described 35 as follows:

Referring to the drawings, 1 represents a frame having terminal bars 22, each bar having two adjacent parallel grooves 3 and 4, respectively, running, preferably, the full length 40 of the bar. Into the inner of said grooves, or groove 3, is inserted and fixed a glass front plate or panel 5, a suitable groove 6 being formed in the lower bar 7 of the frame for the reception of its lower edge. When once 45 inserted, it is permanently secured in the frame by staples 8, driven into the bases of the grooves 3 immediately above the upper edge of the plate. The upper edge of the fixed panel 5 is provided with a protecting-strip 9 of metal, the same being of a form to well embrace the upper edge of said panel. Within the second or outer groove 4 is adapt-

ed to slide the upper rail 10, the said rail having suitable terminal projecting tongues 11, whose upper edges form a continuation 55 of the upper surface of said rail, the lower edges of the tongues terminating at their bases in shoulders 12, whose lower edges form a continuation of the base of the groove 13, receiving the upper edge of the sliding 60 glass plate or panel 14. The plate 14 is additionally supported by the metallic end strips or channels 15 and bottom strip 16, embracing the corresponding edge of the plate, the end strips 15 being each provided at their upper 65 terminals with elongated openings for the free passage therethrough of the tongues 11, the vertical edges of the shoulders 12 abutting against the bases of the channels 15 and the upper edge of the glass 14 bearing against the 70 lower edges of said shoulders, (see Figs. 3 and 4,) whereby a rigid and economical and likewise durable construction is insured. The upper end of the frame is surmounted by a strip 17, respectively secured to the upper ends of the bars 22, the medial portion of the vertical face of said strip being provided with a button 18, which the spring-arms 19 19 of the locking device are adapted to jointly embrace 80 when the panel 14 is pushed to its highest position. The arms 19 19 terminate in curved loops 20 20, adapted to freely ride over the shank of the stud or button 18 for a movement of the panel 14 in either direction, the fixed ends of the springs 19 being secured to 85 the rail 10 by the screw 21, which likewise secures the operating knob or handle 22. Figs. 1 and 2 show the sliding panel closed and locked, and Fig. 6 shows the same open.

In the present device the movable panel 14 90 drops by gravity the moment it is released from the locking stud or button 18 and opens instantly, and this without the use of springs, as in the patent aforesaid; otherwise the entire structure is compact and simplified materially.

Having described my invention, what I claim is—

1. A show-top comprising a suitable frame, a fixed and sliding panel for the same, parallel grooves in the sides of said frame, and a groove at the bottom thereof, an upper rail forming one of the members of the sliding panel and having a lower groove for the re-

ception of the upper edge of the glass forming said panel, a tongue at each end of said rail, and supporting metallic strips having openings for the free passage of the tongues, 5 the latter operating in the grooves formed in the lateral bars of the frame, substantially as set forth.

2. A show-top comprising a suitable frame, a stationary and a sliding panel for the same, 10 parallel grooves in the sides of the frame, and a groove at the bottom thereof for the reception of the lower edge of the stationary panel, an upper rail forming one of the members of the sliding panel and having a lower groove 15 for the reception of the upper edge of the glass forming said panel, a tongue at each end of said rail forming a continuation of the rail, and having a shoulder at the base of the

lower edge thereof whose horizontal or lower edge forms a continuation of the base of the 20 groove formed in said upper rail, supporting metallic strips having openings for the free passage of the tongues, and bearing against the vertical edges of the shoulders, the glass or panel being respectively embraced by said 25 strips, and by the walls of the groove formed in said upper rail, the tongues operating in the grooves formed in the lateral bars of the frame substantially as set forth.

In testimony whereof I affix my signature 30 in presence of two witnesses.

CECELIA H. GOLDMAN.
